UNITED STATES PATENT OFFICE.

RICHARD W. MOSES, OF CORAOPOLIS, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

ROLL-ADJUSTING MECHANISM.

1,388,587.

Specification of Letters Patent. Patented Aug. 23, 1921.

Application filed January 21, 1920. Serial No. 353,040.

To all whom it may concern:

Be it known that I, RICHARD W. MOSES, residing at Coraopolis, in the county of Allegheny and State of Pennsylvania, have invented a new and useful Improvement in Roll-Adjusting Mechanism, of which the following is a full, clear, and exact description, reference being had to the accompanying drawings, forming part of this specification, in which—

Figure 1 is an end elevation of a roll housing and rolls having my invention applied thereto;

Fig. 2 is a vertical section of a portion of the housing and showing the parts which embody the invention; and

Fig. 3 is a section on the irregular line III—III of Fig. 2.

My invention has relation to roll-adjusting mechanism, and more particularly to mechanism for adjusting the lower roll of rolling mills.

The object of my invention is to provide a simple and efficient device of this character which is compact in its arrangement and out of the way, and in which the operative parts are protected from injury by the roll housing.

The nature of my invention will be best understood by reference to the accompanying drawing, in which I have shown the preferred embodiment thereof and which will now be described, it being premised, however, that various changes can be made in the details of construction and arrangement of the parts, without departing from the spirit and scope of the invention, as defined in the appended claims.

In these drawings, the numeral 2 designates one housing of a three-high rolling mill, 3 the lower mill roll, 4 the middle roll and 5 the top roll. 6 is a screw-down device of any usual or suitable character for the top roll. The bottom roll 3 is mounted in a housing for vertical adjustment in any suitable manner. Its end bearing 7 is supported by a saddle block 8, resting on the upper end of a vertical adjusting screw 9, which has a threaded portion 10, mounted to turn in a fixed nut 11, seated in the housing 2. The lower end of the screw 9 extends below the housing proper and has slidably secured thereto a flanged gear 12, formed with internal beveled gear teeth 13, the hub of the

pinion being shown as having a step-bearing 55 in a removable cap 14, upon the anti-friction rollers 15.

16 is a bevel pinion whose teeth are in mesh with the teeth 13 of the gear 12, and which is rigidly secured to the lower end 60 portion of a shaft 17, which extends obliquely upward through the roll housing 2, in which it is provided with bearings at 18 and 19. The upper end of this shaft, which projects above the base portion of the housing, is shaped to form a wrench seat 20, for a removable actuating wrench 21. The wrench may be locked in different positions by means of a removable pin 22, extending through the wrench handle and into engagement with any one of a plurality of openings 23, in the sector plate 24, secured to the housing base.

The operation will be readily understood. When it is desired to adjust the lower roll 75 3, the wrench is actuated to thereby actuate the gear 12 and screw shaft 11, to raise or lower the roll bearing and roll.

It will, of course, be understood that in practice a similar device is employed at 80 each end of the mill.

The advantages of my invention will be apparent to those skilled in the art. The device is simple. The actuating mechanism is thoroughly protected by reason of 85 its location within the housing. Furthermore, it is out of the way and does not form an obstruction to other operations about the mill, as is the case with adjusting devices which project at the end of the mill. It also 90 enables the obtaining of a relatively large gear ratio in a small space. The housing base is utilized as a bearing for the actuating shaft and the device can be applied at a relatively low cost.

I claim:

1. The combination with a roll housing and a mill roll mounted for vertical movement therein, of an adjusting shaft for said roll extending upwardly through the base of the housing, an actuating shaft extending obliquely in a lateral and upward direction through the base of the housing, an internal bevel gear on said adjusting shaft and said actuating shaft having a pinion engaging 100 said internal gear, and means for operating the actuating shaft, substantially as described.

2. The combination with a roll housing and a mill roll mounted for vertical movement therein, of an adjusting shaft for said roll extending upwardly through the base 5 of the housing, an actuating shaft extending obliquely in a lateral and upward direction through the base of the housing, an internal bevel gear on said adjusting shaft and said actuating shaft having a pinion engaging 10 said internal gear, and means for operating the actuating shaft, said gearing being below the housing proper, and a removable cap inclosing said gearing, substantially as described.
- 15 3. The combination with a roll housing and a mill roll mounted for vertical movement therein, of an adjusting shaft for said roll extending upwardly through the base of the housing, an actuating shaft extending 20 obliquely in a lateral and upward direction through the base of the housing, an internal bevel gear on said adjusting shaft and said actuating shaft having a pinion engaging

tion through the base of the housing, an internal bevel gear on said adjusting shaft and said actuating shaft having a pinion engaging said internal gear, and means for operating the actuating shaft, said gearing being 25 below the housing proper, and a removable cap inclosing said gearing, said cap having a step-bearing for the adjusting shaft, substantially as described.

4. In a rolling mill, the combination with 30 a vertically adjustable roll, and an adjustable member carrying said roll, of a shaft journaled in the base of the housing and extending laterally upward through said base, and bevel gearing connecting the adjusting 35 shaft with said member, substantially as described.

In testimony whereof, I have hereunto set my hand.

RICHARD W. MOSES.
